[57] CLAIM

The ornamental design for a ski seat having C-shaped support, as shown and described.

DESCRIPTION

FIG. 1 is a front perspective view of a ski seat having a C-shaped support showing the design;
FIG. 2 is a right side elevational view of the design of FIG. 1, the left side elevational view thereof being identical;
FIG. 3 is a top plan view of the design of FIG. 1;
FIG. 4 is a front elevational view of the design of FIG. 1;
FIG. 5 is a rear elevational view of the design of FIG. 1;
FIG. 6 is a front perspective view of a second embodiment showing the design;
FIG. 7 is a top plan view of the design of FIG. 6;
FIG. 8 is a front elevational view of the design of FIG. 6;
FIG. 9 is a front perspective view of a third embodiment showing the design;
FIG. 10 is a right side elevational view of the design of FIG. 9, the left side elevational view thereof being identical;
FIG. 11 is a top plan view of the design of FIG. 9; and,
FIG. 12 is a front elevational view of the design of FIG. 9.
